SLIDER FOR SLIDE FASTENERS

Alfred E. Carlile, Meadville, Pa., assignor to Talon,
Inc., a corporation of Pennsylvania

Application February 24, 1940, Serial No. 320,618

10 Claims. (Cl. 24—205.5)

This invention relates to slide fasteners and, in particular, to the provision therein of a slider construction embodying new and improved locking means selectively operable for locking the slider in desired predetermined position with respect to the fastener.

It is an object of this invention to provide such a slider which is simple, cheap, durable and strong and which possesses all of the functional qualities necessary for adapting it for use in clothing.

It is a further object of this invention to provide such a slider wherein the pull tab of the slider is provided with improved locking means directly engageable with the interlocking fastener members of the slide fastener in a novel manner, achieving new and advantageous results.

It is a further object of this invention to provide such a slider construction wherein the locking means, which directly engages the interlocking fastener members of the fastener, cooperates therewith in such manner as to avoid damage and defacement of the surfaces of the interlocking fastener members, and wherein the locking means inherently resists accidental locking of the slider when unlocked and/or accidental unlocking of the slider when locked.

It is a further object of this invention to provide such locking means which is long-wearing, and but little subjected to wear, and which cooperates with the interlocking fastener members of the fastener in the unlocked position of the pull tab, in such manner as to avoid impairment of the free sliding properties of the unlocked slider.

These and other objects and advantages of the invention will appear from the following description taken in conjunction with the accompanying drawing which forms a part thereof, and will be pointed out in the appended claims.

In the drawing:

Fig. 1 is a perspective view, partly broken away and partly in section, of a slider constructed according to this invention, on the stringers of a slide fastener;

Fig. 2 is a horizontal section through the slider of Fig. 1, showing the parts in unlocked position, as in Fig. 1;

Fig. 3 is a view similar to Fig. 2, but showing the parts in locking position;

Fig. 4 is a longitudinal section taken substantially on the line 4—4 of Fig. 2, with the right-hand fastener stringer omitted in the interest of clearness;

Fig. 5 is a longitudinal section taken substan-

tially on the line 5—5 of Fig. 3, with the right-hand stringer omitted in the interest of clearness; and

Fig. 6 is a perspective view of a single interlocking fastener member, shown in Fig. 1, detached from its supporting stringer tape in order best to illustrate the details thereof.

Certain problems have been encountered in the use, on certain articles of clothing, such as men's trousers, of conventional sliders provided with manually actuated locking pins secured to the pull tab of the slider. When such sliders are brought to partially open position and the pull tabs accidentally released or removed somewhat from unlocked position, the pin will often fall automatically into locking position between adjacent interlocking fastener members and subsequent application of tearing stress upon the fastener, tending to urge the slider longitudinally of the fastener, will place substantial strain upon the interlocking fastener members adjacent the locking pin tending to impair the firmness of attachment of the interlocking fastener members to the stringer tape. For this reason, it is desirable that such locking means be provided, as will inherently resist unintentional assumption of the locked position.

Furthermore, in the use of such pin lock sliders, as described above, the slider is sometimes brought to a terminal position wherein the pin will engage the exterior flat side surface of a locking member instead of entering the space between adjacent interlocking fastener members. In such cases the application of pressure to the pull tab is resisted by this engagement of the pin with the exterior side surface of the interlocking fastener member. In order properly to lock the slider in position and to bring the pull tab thereof to locked position, it is necessary to move the slider to such position that the pin will fall into locking position between adjacent interlocking fastener members. The application of force to the pull tab, instead of movement of the slider, will often result in serious damage to the fastener and/or locking pin thereof.

According to the principles of this invention, the above disadvantages are totally obviated by the provision of such locking means as is herein described and illustrated. The lock slider, according to this invention, may not readily be dislodged from its position unintentionally and cannot accidentally assume a locked position when the fastener is partly open.

The locking member, in its unlocked position, slides or skids upon the flat side surface por-

tions of the interlocking fastener members in such manner that the fastener may be opened by stripping when the locking means is in unlocked position. In other words, the stringers 5 may be pulled apart above the slider and the slider caused to move downwardly with respect to the stringers, during which movement the operative surface of the locking member skids or slides upon the flat side surfaces of the interlocking fastener members without ratcheting.

The cooperative relationship of the locking member with respect to the fastener members is such that substantial force is necessitated for placing it in locking position with respect to the 15 interlocking fastener members.

In its locking position, the operative surface of the locking member extends inwardly beyond the plane of the exterior flat side surfaces of the interlocking members. For this reason, in order to 20 secure this penetration of the locking member within the plane of the flat surface portions, it is necessary to exert such force upon the pull tab as to overcome the resiliency of the locking member and cause the locking portion thereof to be 25 snapped into locking position to engage the inclined surfaces of the head or nose portions of the interlocking fastener members.

This movement of the locking member from 30 unlocked position to locked position requires translation or longitudinal movement as well as rotary movement of the locking member. This translation is necessary in order that the locking member be moved from that portion of the fastener where it bridgingly engages the flat side 35 surfaces of the interlocking fastener members, upwardly to that portion of the fastener where the flat side surfaces of the interlocking fastener members are sufficiently widely spaced to permit the locking member to move between the spaced flat side surfaces into engagement with the inclined surfaces of the head portions of the interlocking fastener members. This combined rotary and translatory movement of the locking member from unlocked to locked position is, of course, resisted by the inherent resilience of the locking 45 member. This totally prevents accidental locking of the slider.

In Fig. 1, a slider constructed according to the principles of this invention, is shown in position on the component parts of a conventional slide fastener. The fastener shown includes similar stringers 10, suitably connected at their lower ends and provided with suitable top stop means at their upper ends (not shown). Each stringer 10 comprises stringer tapes 11 having one edge 11a thereof reinforced and thickened in suitable manner as by cords 12 attached thereto at opposite sides. Secured on the thickened edge 11a of the tapes 11 are interlocking fastener members 14. The interlocking fastener members 14 of the stringers 10 are progressively engaged to connect the stringers 10 by longitudinal movement of the slider 30 upwardly with respect to the stringers 10 and progressively disengaged to disconnect the stringers 10 by downward movement of the slider 2 with respect to the stringers 10, as seen in Figs. 2 and 3.

As shown in Fig. 6, each interlocking fastener member 14 has two main portions, namely, the head portion 15 and the bifurcated leg portion 16. The head portion 15 is formed by an upwardly directed projection of generally conical form having inclined surfaces 18. Concentric with this projection, which may be termed the "crown" of the interlocking fastener member 14, is a pocket

19 leading from the bottom surface 20 of the member 14 and having interior surfaces substantially complementary with the surfaces 18 in order to secure the interlocking cooperation shown in Figs. 1, 2 and 3.

The flat top surface 21 of the fastener member 14 extends from the rear of the leg portion 16 to a point adjacent the head projection, being substantially parallel with the flat bottom surface 20 of the fastener member 14. The flat side surfaces 22 are substantially parallel and extend between the top and bottom surfaces 20 and 21 and from end to end of the fastener member 14.

Extending inwardly from the rear or outer surface 23 of the leg portion 16 of each interlocking fastener member 14 is the stringer tape-receiving slot 24 intermediate the legs 25, which slot terminates inwardly in a substantially cylindrical bead-receiving channel 26. When the fastener members 14 are secured to the tapes 11, the reinforced edges 11a of the tapes 11 are disposed in the channels 26 and the stringer tapes 11 extend outwardly between the legs 25, through the tape-receiving slots 24.

The slider body is generally designated 30 and 25 comprises a rear wing member 31 and front wing member 32. The rear wing member 31 is provided with marginal side flanges 33, and the front wing member 32 is provided with similar side flanges 34. These side flanges 33 and 34 cooperate with the wedge member or neck member 35 to form an upwardly diverging, substantially Y-shaped interlocking fastener member-receiving channel, as shown in Figs. 2 and 3.

In the lower end of this interlocking member-receiving and guiding channel, the interlocking members 14 of the stringers 10 of the slide fastener are interlocked or in substantially interlocked position, as shown in Figs. 2 and 3, while the upper branches of this channel separate the 40 stringers or cause them to diverge whereby the interlocking fastener members are disengaged and spaced, progressively upward, from one another.

The rear wing and front wing are of similar 45 outline and are, as above described, substantially parallel. The rear wing 31 is uninterrupted or continuous, while the upper wing 32 is provided with a centrally disposed locking member-receiving aperture 36 which is preferably substantially 50 rectangular. At each side of the aperture 36 is an upstanding lug 37 which provides for swingable attachment of the pull tab 40 to the slider body 30.

The pull tab 40, preferably of flat or plate-like 55 form, is provided with legs or extensions 41 having transverse projections at their extremities which form trunnions 42 which extend between the lugs 37 and the wall of the front wing 32 to secure swingable attachment of the pull tab 40 to the slider body 30.

Between the legs or extensions 41, the pull tab 40 is provided with a central integral locking tongue member 43 of bent or curled-over form. An intermediate flattened bearing surface 44 is provided on the locking tongue member 43 and this bearing surface bridgingly engages and skids or slides upon the adjacent flat side surfaces 22 of the interlocking fastener members 14 in the unlocked position of the slider, as shown in Figs. 70 2 and 4.

The end extremity 45 of the locking tongue member 43 is substantially more acutely arcuate than the intermediate flattened bearing surface 44 and projects inwardly beyond the plane of the 75

flat side surfaces 22 of the interlocking fastener members 14 in the locked position of the slider, as shown in Figs. 3 and 5. Comparison of Figs. 2 and 3 will clearly illustrate that upper translatory movement of the locking tongue member 43 with respect to the slider is necessary to move the pull tab 40 from unlocked position (Figs. 2 and 4) to locked position (Figs. 3 and 5).

It is necessary, in moving the locking tongue 10 43 from unlocked to locked position, that the locking tongue member 43 be moved beyond that portion of the fastener where the flat side surfaces 22 of the interlocking members are sufficiently closely spaced as to be engaged bridgely 15 by the contacting surface of the locking tongue 43 to a portion of the fastener where the flat side surfaces 22 are sufficiently widely spaced to permit the locking tongue 43 to extend therebetween and project within the plane of the flat 20 side surfaces 22 lockingly to engage the inclined surfaces 18 of the interlocking fastener members 14, as shown in Figs. 3 and 5.

In other words, the locking tongue member 43 must be swung from a position below the locking axis indicated by the line L—L in Figs. 2 and 3 (see Fig. 2) upwardly beyond the locking axis L—L substantially to the position shown in Fig. 3. Appreciable resistance to this movement is, of course, encountered due to the necessity for snapping the locking tongue member 43 upwardly beyond those portions of the flat side surfaces 22 which are bridgely engaged by the locking tongue member 43. This resistance is, of course, dependent upon the degree of inherent resiliency in the locking tongue member 43 which may be varied, as desired.

From the above, it will be clearly understood that accidental locking of the slider is prevented by the necessity for overcoming the inherent resiliency in the locking tongue member to bring the pull tab from unlocked to locked position. Likewise, when the pull tab is in locked position, as shown in Figs. 3 and 5, the end extremity 45 of the locking tongue member 43 inherently 5 engages the inclined surfaces 18 of an interlocking fastener member 14 to resist swinging movement of the pull tab 40, thus requiring exertion of appreciable force to return the pull from locked position (Figs. 3 and 5) to unlocked position (Figs. 2 and 4).

The intermediate flattened bearing surface 44 skids along the flat side surfaces 22 of the interlocking fastener members 14 in the unlocked position of the slider, as shown in Figs. 1, 2 and 4, and due to the smoothness of this bearing surface, which terminates at each end in progressively more arcuate surfaces, damage to the flat side surfaces of the interlocking fastener members 14 is prevented.

Likewise, when the slider is in unlocked position, transverse separating pull may be exerted upon the stringers 10 above the slider to cause free stripping, wherein the slider moves downwardly of the stringers 10 in response to such transverse pull, with no danger whatever of the occurrence of accidental locking or damage, such as would be encountered where the locking element was of pin form which would ratchet upon the interlocking fastener members and, probably, fall between a pair of adjacent interlocking fastener members to lock the slider to at least one stringer, whereupon the stripping force would be translated into strain tending to pull the interlocking fastener members 14 from the supporting stringer tapes 11.

The above-described lock slider is extremely simple, rugged and cheap. The locking tongue member 43 may be readily, conveniently and cheaply attached to or formed integrally with the pull tab 40 which is otherwise of conventional form and which is secured to the slider body in conventional manner.

In addition to these advantages, the inherent resiliency of the locking tongue is utilized to oppose accidental movement of the pull tab, 10 both from locking to unlocking position and from unlocking position to locking position.

Furthermore, the nature of the resilient locking tongue member and its cooperation with the flat side surfaces and inclined nose surfaces of 15 the interlocking fastener members is such as to prevent damage to these surfaces which would result in undue wear and damage to the fastener.

It is, of course, to be understood that the above-described structure is merely illustrative and in nowise limiting and that I desire to comprehend within my invention all modifications included within the scope of the appended claims.

Having thus fully described my invention, what I claim as new and desire to secure by Letters Patent is:

1. In a slide fastener, a slider body having therein a diverging fastener member receiving channel and an aperture communicating with said channel, a pair of stringers in said channel each comprising a stringer tape with attached spaced fastener members, said fastener members each having flat side surfaces and head portions with inclined surfaces, a pull tab member hinged to said slider body, and a yieldable locking tongue on said pull tab extending into said aperture and directly engaging fastener members in said channel, said locking tongue having a relatively flat portion slidably engaging the flat side surfaces of said interlocking fastener members in the unlocked position of said pull tab and having a relatively acutely arcuate portion engaging the inclined surfaces of said fastener members in the locking position of said pull tab for locking said slider against movement on said stringers. 30 40 45

2. In a slide fastener, a slider body having therein a diverging fastener member receiving channel and an aperture communicating with said channel, a pair of stringers in said channel each comprising a stringer tape with attached spaced fastener members, said fastener members each having flat side surfaces and head portions with inclined surfaces, a pull tab member hinged to said slider body, and a yieldable locking tongue on said pull tab extending into said aperture 50 55 and directly engaging fastener members in said channel, said locking tongue having a gently curved portion bridging and slidably engaging the flat side surfaces of adjacent interlocking fastener members in the unlocked position of said pull tab and having a relatively acutely arcuate portion engaging the inclined surfaces of said fastener members in the locked position of said pull tab for locking said slider against movement on said stringers, said pull tab being manually 60 65 movable from said first position to said second position, and said movement being resisted by the yieldability of said locking tongue.

3. In a slide fastener, a slider body having therein a diverging fastener member receiving 70 channel and an aperture communicating with said channel adjacent the zone of divergence, a pair of stringers in said channel each comprising a stringer tape with attached spaced fastener members, said fastener members each having leg 75

portions with flat side surfaces and head portions with inclined surfaces, a pull tab member hinged to said slider body adjacent said aperture, and a resilient locking tongue on said pull tab extending into said aperture and directly engaging fastener members in said channel, said locking tongue having a gently curved portion bridgingly engaging the flat side surfaces of said fastener members in the unlocked position of said pull tab and having a relatively more acutely curved portion lockingly engaging the inclined surfaces of said fastener members between spaced flat side surfaces in the locked position of said pull tab for locking said slider against movement on said 15 stringers.

4. In a slide fastener, a slider body having therein a diverging fastener member receiving channel and an aperture communicating with said channel adjacent the zone of divergence, a 20 pair of stringers in said channel each comprising a stringer tape with attached rows of spaced fastener members, said fastener members each having leg portions with flat side surfaces and head projections with conical surfaces, a pull 25 tab member hinged to said slider body adjacent said aperture and a resilient locking tongue on said pull tab extending into said aperture and directly engaging fastener members in said channel, said locking tongue having a flattened portion bridgingly and slidably engaging the flat side 30 surfaces of adjacent interlocking fastener members in the unlocked position of said pull tab and having a relatively acutely arcuate end portion projectible inwardly of the plane of the flat 35 side surfaces into locking engagement with the conical surfaces of said interlocking members.

5. In a slide fastener, a slider body having therein an upwardly diverging fastener member receiving channel and an aperture communicating 40 with said channel adjacent the point of divergence, a pair of stringers in said channel each comprising a stringer tape with attached spaced interlocking fastener members, said interlocking fastener members each having leg portions with flat side 45 surfaces and head portions with inclined surfaces, a pull tab member hinged to said slider body adjacent said aperture, and a resilient locking tongue on said pull tab extending into said aperture and directly engaging interlocking fastener members in said channel, said locking tongue being eccentric with respect to the pivot 50 axis of said pull tab and having an intermediate relatively flat portion and a relatively acutely arcuate end extremity, said flattened portion bridgingly engaging the flat side surfaces of said 55 interlocking fastener members and skidding freely thereon in the unlocked position of said pull tab, and said end extremity extending inwardly of the plane of the flat side surfaces of the interlocking fastener members into firm locking engagement with the inclined surfaces of the head portions of said interlocking fastener members in the locking position of said pull tab.

6. In a slide fastener, a slider body having 65 therein an upwardly diverging fastener member receiving channel and an aperture communicating with said channel adjacent the point of divergence, a pair of stringers in said channel each comprising a stringer tape with attached spaced 70 interlocking fastener members, said interlocking fastener members each having leg portions with flat side surfaces and head portions with inclined surfaces, a pull tab member hinged to said slider body adjacent said aperture, and a resilient locking tongue on said pull tab extending into said 75

aperture and directly engaging interlocking fastener members in said channel, said locking tongue being eccentric with respect to the pivot axis of said pull tab and having an intermediate relatively flat portion and a relatively acutely 5 arcuate end extremity, said flattened portion bridgingly engaging the flat side surfaces of said interlocking fastener members and skidding freely thereon in the unlocked position of said pull tab, and said end extremity being snapped inwardly of the plane of the flat side surfaces of the interlocking fastener members into firm locking engagement with the inclined surfaces of the head portions of said interlocking fastener members by manual swinging movement of said 15 pull tab into locking position against the inherent resiliency of said locking tongue, and the inherent resiliency of said locking tongue resisting return of said pull tab from locking position to unlocked position.

7. In a slide fastener, in combination with a pair of stringers comprising stringer tapes with interlocking fastener members spacedly attached to one edge thereof, said interlocking fastener members having leg portions straddling said tape edges with flat side surfaces and having head portions with inclined surfaces; a slider slidable on said stringers for progressively connecting and disconnecting said stringers by engaging and disengaging the head portions of said interlocking 30 fastener members, said slider including a body with a diverging fastener member receiving channel therein, and an aperture leading to said channel adjacent the zone of divergence, a pull tab hingedly attached to said slider body adjacent 35 said aperture, and a resilient locking tongue on the inner end of said pull tab projecting into said aperture, said locking tongue having a flattened portion bridgingly and slidably engaging the flat side surfaces of said interlocking fastener 40 members in the unlocked position of said pull tab and having a relatively acutely arcuate end extremity projectible inwardly of the plane of the flat side surfaces into locking engagement with the inclined surfaces of the head portions of 45 said interlocking fastener members between spaced flat side surfaces, the movement of said pull tab and said locking tongue between unlocked and locking positions being resisted by the inherent resiliency of said locking tongue. 50

8. In a slide fastener, in combination with a pair of stringers comprising stringer tapes with interlocking fastener members spacedly attached to one edge thereof, said interlocking fastener members having leg portions straddling said tape 55 edges with flat side surfaces and having head portions with inclined surfaces; a slider slidable on said stringers for progressively connecting and disconnecting said stringers by engaging and disengaging said interlocking fastener members, 60 said slider including a body having therein an upwardly diverging channel slidably supporting said stringers, said body having an aperture leading to said channel adjacent the zone of divergence, a pull tab hingedly attached to said slider body adjacent said aperture, and a resilient locking tongue on the inner end of said pull tab projecting into said aperture, said locking tongue having a flattened portion bridgingly and 65 slidably engaging the flat side surfaces of said interlocking fastener members in the unlocked position of said pull tab and having a relatively acutely arcuate end portion projectible upwardly of the slider and inwardly of the plane of the flat side surfaces of the interlocking fastener 70

members into locking engagement with the inclined surfaces of the head portions of said interlocking fastener members, the movement of said pull tab and said locking tongue between 5 unlocked and locking positions being resisted by the inherent resiliency of said locking tongue, and the inherent resiliency of said locking tongue maintaining firm engagement between the arcuate end portion of said locking tongue and the 10 inclined surfaces of the head portions of said interlocking fastener members in locking position.

9. In a slide fastener slider including a body having a channel slidably supporting interlocking slide fastener members of fastener stringers, said body having an aperture communicating with said channel; a pull tab hinged to said slider body adjacent said aperture, and a resilient locking tongue on said pull tab, said locking 20 tongue bridgingly engaging the flat side surfaces of adjacent interlocking fastener members in the unlocked position of said pull tab and lockingly engaging inclined surfaces of said fastener members in the locking position of said pull tab for 25 locking said slider against movement on said stringers, said pull tab being manually movable from said unlocking position to said locking position and said movement thereof being resisted by yieldable resiliency of said locking tongue.

10. In a slide fastener slider including a body having therein a channel slidably supporting interlocking fastener members of the stringers of a fastener, said body having an aperture communicating with said channel; a pull tab pivoted to said slider body, adjacent said aperture, and a resilient locking tongue on said pull tab, said locking tongue being eccentric with respect to the pivot axis of said pull tab and having an intermediate relatively flat portion and a relatively acutely arcuate end extremity, said flattened portion bridgingly engaging the flat side surfaces of said interlocking fastener members and skidding freely thereon in the unlocked position of said pull tab, and said end extremity 15 being movable upwardly of the plane of the flat side surfaces of the interlocking fastener members into firm locking engagement with the inclined surfaces of said interlocking fastener members by manual swinging movement of said pull tab into locking position against the inherent resiliency of said locking tongue, and the inherent resiliency of said locking tongue resisting return of said pull tab from locking position to unlocked position while 20 maintaining firm engagement between said end extremity and the inclined surfaces of said interlocking fastener members. 25

ALFRED E. CARLILE.
